THOMAS HOUGHTON, OF PHILADELPHIA, PENNSYLVANIA.

Design No. 3,372, dated February 16, 1869.

DESIGN FOR A LAMP-CHIMNEY.

The Schedule referred to in these Letters Patent and making part of the same.

To all whom it may concern:

Be it known that I, THOMAS HOUGHTON, of the city and county of Philadelphia, and State of Pennsylvania, have invented a new and original Design for Lamp-Chimneys; and I do hereby declare that the accompanying drawing fully illustrates my said design.

Having thus described my invention,

What I claim as new, is—

The design for lamp-chimney, as herein shown and set forth.

To the above I have signed my name, this 8th day of January, 1869.

THOMAS HOUGHTON.
